MAGNETIC GAME OF SKILL

Alfred Fraser Washburn, Old Tappan, N.J.

Application March 4, 1958, Serial No. 719,028

4 Claims. (Cl. 273—1)

This invention concerns a magnetic game of skill. The game includes a base plate or baseboard on which is adjustably positioned a plurality of loosely coiled, very flexible springs. The springs project upwardly from the baseboard. At the free end of each spring is mounted a permanent magnet. The magnets are oriented so that the poles of like polarity are located at the forward opposed ends of the magnets. These springs, with their magnets, are the "guards" of the game. A central area of the baseboard between the springs is enclosed by a fence. Within the fence is loosely and removably placed a body of paramagnetic metal. This body is the "treasure" of the game. A wand having a strong permanent magnet mounted in one end thereof and extending outwardly thereof is provided for playing the game. The magnet in the wand is oriented with its forward outer end having a polarity the same as that of the forward opposed ends of the spring mounted magnets. This wand is the "catcher."

To play the game, the player must reach the treasure with the magnetic protruding end of the catcher and remove the treasure from the fenced area without either of the guards interfering; that is, neither of the spring mounted magnets may touch the wand or metal body. Normally, the springs tend to overhang the fenced area to guard the treasure disposed therein. The spring mounted magnets are surrounded by concentrated magnetic fields which overlap each other. The magnetic field surrounding the wand magnet is also quite strong. Upon approach of the tip of the catch toward the magnets, said magnets will be repelled from the wand, but upon continued inward movement of the wand toward the treasure and when the wand is positioned approximately over the treasure, the inner end of the magnet in the wand will attract the spring mounted magnets and because of this the guards may capture the treasure before the catcher.

If a player is successful in inserting the catcher wand into the fenced area to "capture the treasure" and to remove it without contact by either guard, he has scored a point in the game. Players take turns in attempting to score a maximum number of points representing successful captures of the treasure. After each capture, the treasure is replaced within the fenced area and a new attempt is made by a player to capture it. Because of the strong magnetic fields involved, considerable skill will be required to capture the treasure without interference by the guards.

It is, therefore, a principal object of the invention to provide a magnetic game in which a loose removable paramagnetic body is guarded by a spring mounted permanent magnet from capture by a permanent magnet carried on a wand.

A further object is to provide a game with a plurality of very flexible springs adjustably mounted on a baseboard, each of the springs carrying a permanent magnet at the free end thereof, the magnets being oriented with poles of like polarity outermost.

A still further object is to provide a game having an

2

area thereof enclosed by a fence and having a metal body loosely disposed therein, with flexible springs carrying permanent magnets at their ends arranged on the baseboard to overhang the body in mobile suspension.

5 Another object is to provide a game of the character described further provided with a rod or wand carrying a permanent magnet at one end, one end of the magnet being adapted to repel and the other end being adapted to attract the magnets carried by the springs.

10 For further comprehension of the invention, and of the objects and advantages thereof, reference will be had to the following description and accompanying drawings, and to the appended claims in which the various novel features of the invention are more particularly set forth.

15 In the accompanying drawings forming a material part of this disclosure:

Fig. 1 is a perspective view of a game embodying the invention.

20 Figs. 2 and 3 are sectional views on an enlarged scale taken on lines 2—2 and 3—3, respectively, of Fig. 1.

Fig. 4 is a sectional view taken on lines 4—4 of Fig. 2. Fig. 5 is a side view partially in section of the wand and magnet carried thereby.

25 Fig. 6 is a sectional view taken on lines 6—6 of Fig. 5.

Fig. 7 is a view similar to Fig. 2 showing a portion of the baseboard with spring removed.

30 Fig. 8 is a top plan view of another form of the game. Referring to the drawings, there is shown in Fig. 1 a generally rectangular flat wood block 10 which serves as

35 a baseboard for the game. In the upper surface of the block are formed circular grooves 12 and 14 spaced apart and located near opposite ends of the block. Each groove has an arcuate cross section which extends circumferentially through angle A which is slightly more than 180° as best shown in Fig. 7. Each groove is formed with short straight inwardly extended sides 16. Disposed in the grooves are the end portions of coiled wire springs 18 and 20. The springs are inserted in the grooves by

40 forcing them past the flat edges 16 so that they become engaged in the grooves with the remainder of the body portions 22, 24 extending upwardly out of the grooves. The points at which the body portions of the springs extend out of the grooves may be changed by sliding each spring around the groove. The springs are thus

45 adjustably located in the grooves. Also, the body portions can be made longer or shorter by disposing more or less of the end portions in the grooves.

At the free end of each spring is secured a permanent magnet 26 by means of a suitable cement joint 28. The springs are so placed that they will normally overhang

50 a central region or area of the block with magnets 26 in mobile suspension thereover. In this region is located a low fence 30 formed of cardboard, fiberboard or other non-magnetic material. The fence may be rectangular, circular or have any other continuous geometrical shape.

55 Each of magnets 26 is oriented with one pole, for example the N pole at its most forwardly extending end. Since the ends of the magnets on each spring have the same polarity, they will repel each other and not engage, as indicated in Fig. 1.

60 Within the fence is placed a removable body 33 containing a piece of paramagnetic metal 32. If desired, this metal may be enclosed wholly or partially in a plastic or painted cover 34 as shown in Fig. 3. To lend realism to the game, the magnets may be painted at

65 as shown in Figs. 1, 2 and 4, to resemble snake heads and the body 33 may be formed in the shape of a miniature skull. Each of the magnets 26 will be attracted toward the body 33 but this attraction will be resisted by the inherent resiliency in the bodies of the springs which simulate snakes.

In order to play the game, there is provided a wood

or plastic wand in the form of a cylindrical rod 36, best shown in Figs. 5 and 6. Inserted in one end of the rod is a cylindrical permanent magnet 38. This magnet is oriented with its outer end or outer pole N of the same polarity as that of the forward ends of the magnets 26 so that when the wand is thrust into the fence to capture the body 33, with its leading tip directed toward the spring mounted magnets 25, the approaching tip will repel the magnets 26. However, continued movement of the wand into the fence toward the treasure T will bring the other end of the magnet 38 within the area of the magnets 26 and thereby attract said magnets whereby said magnets 26 may capture the treasure before the magnet 38 of the wand. Thus, any attempt made by the player to thrust the wand into the fence to capture body 33 will be subject to interference by the spring mounted magnets which are suspended in their mutually overlapping magnetic fields so that they are mobile in three planes or dimensions. With some practice the player can learn to thrust the "catcher" C in underneath the "guards" G to capture the "treasure" T and remove it before the "guards" can overcome their inertia and respond to intercept the capture. The magnets 26 will tend to follow magnet 38 toward body 33 so that the capture will require some dexterity and skill.

One or more magnet carrying rods 36 may be used to play this game in which the shapes and lengths of the body members 22 and 24 may be changed as desired.

While the game is illustrated in Fig. 1 as having only two guards G and is played with one catcher C, it is possible to have four guards G and two catchers C, as shown in Fig. 8. A single treasure T will still be used disposed in the ring 30^a, here shown as circular. The player will manipulate the two catchers until one of them captures the treasure T. Since there are now four guards to avoid, greater dexterity will be required of the player to score a point by capturing the treasure without interception by the guards. Each of the permanent magnets 26 and permanent magnets 38 in the game of Fig. 8 are oriented similarly to the magnets 26 and 38, respectively, of the game of Fig. 1 so that four magnets 26 are influenced by the movements of magnets 38 as they enter the overlapping moving magnetic fields of magnets 26.

The magnets 26 may either be shaped to form the head of a snake or the like, or a suitable permanent magnet may be enclosed in a plastic or other material shaped to simulate the snake head or the like.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. A magnetic game, comprising a nonmagnetic baseboard having an upper flat surface, said baseboard having a plurality of closely spaced circular grooves in said surface, a plurality of coil springs respectively anchored at one end in the grooves, with said one end being slidably adjustable in the groove, a permanent magnet mounted at the other free end of each spring in suspension so that the magnets are free to move over the

space between the grooves, a confined body of paramagnetic metal removably disposed on said surface in the space between the grooves, and at least one cylindrical nonmagnetic wand carrying a permanent magnet at the free end thereof, said wand being adapted to reach said body for engagement by said latter magnet, the magnets carried by said springs tending to interfere with said engagement.

2. In a magnetic game of skill, a support, a body of paramagnetic metal, removably disposed on the support, a plurality of springs mounted on the support, said springs carrying permanent magnets having magnetic fields which overlap each other, engagement between said body and each of the magnets being prevented by resisting resilience in each spring, and a wand carrying a permanent magnet and adapted to engage said body on being thrust through said magnetic fields, the magnets carried by said springs tending to intercept engagement of the body by said wand magnet.

3. In a magnetic game of skill, a support, a body of paramagnetic metal removably disposed on the support, a plurality of springs mounted on the support, said springs carrying permanent magnets having magnetic fields which overlap each other, engagement between said body and each of the magnets being prevented by resisting resilience in each spring, and a wand carrying a permanent magnet and adapted to engage said body on being thrust through said magnetic fields, the magnets carried by said springs tending to intercept engagement of the body by said wand magnet, the magnets carried by the spring having forward opposed ends of like polarity so that said forward ends repel each other and keep the spring mounted magnets freely and mobilely suspended over said body.

4. In a magnetic game of skill, a support, a body of paramagnetic metal removably disposed on the support, a plurality of springs mounted on the support, said springs carrying permanent magnets having magnetic fields which overlap each other, engagement between said body and each of the magnets being prevented by resisting resilience in each spring, and a wand carrying a permanent magnet and adapted to engage said body on being thrust through said magnetic fields, the magnets carried by said springs tending to intercept engagement of the body by said wand magnet, the magnets carried by the springs having forward opposed ends of like polarity so that said forward ends repel each other and keep the magnets freely and mobilely suspended over said body, said wand magnet having a free end with a polarity similar to the polarity of the forward opposed ends of the magnets carried by the springs so that said spring mounted magnets tend to follow said wand magnet when the latter is thrust through said magnetic fields to engage the body of paramagnetic metal.
